UNITED STATES PATENT OFFICE.

CHARLES L. TURNER, OF LOS ANGELES, CALIFORNIA.

BOTTLE CLOSURE.

Application filed March 9, 1922. Serial No. 542,221.

To all whom it may concern:

Be it known that I, CHARLES L. TURNER, a citizen of the United States, residing at Los Angeles, in the county of Los Angeles and State of California, have invented a new and useful Improvement in Bottle Closures, of which the following is a specification.

My invention relates to bottle closures and more particularly to bottles in which milk or cream are commonly sold. It is the practice throughout the United States to furnish milk or cream to the consumer in a glass bottle which is provided with a paste board cap, this cap being slightly larger than the top of the bottle so that it is frictionally retained in place therein. These paper caps are somewhat difficult to remove, the usual method now in use being to drive a pointed instrument through the center of the cap which is then pried upwardly.

It is an object of my invention to provide means by which the caps may be readily removed.

It is a further object of my invention to provide a removing means which will be extremely cheap to install and which can be readily put in place during the operation of capping the bottles which is ordinarily accomplished by automatic machinery.

Further objects and advantages will be made evident hereinafter.

Referring to the drawing which is for illustrative purposes only,

Fig. 1 is a perspective view of a milk bottle equipped with my invention.

Fig. 2 is a view showing the method of removing the cap.

In the form of the invention shown a milk

bottle 11 having a neck 12 is provided with a stepped opening 13 into which an ordinary paste board cap 14 may be inserted, the members 12 to 14 being old in the art.

In the practice of my invention I place across the top of the bottle a piece of string 15 which is heavily impregnated with paraffine or the like, this string 15 being forced down during the operation of capping so that it lies under the cap 14 with the two ends 16 and 17 of the string projecting at each side of the cap. These two ends are allowed to project as shown in Fig. 1 until it is desired to remove the cap which may be conveniently done by placing the thumb 20 of the right hand on the end 17 of the string and pulling upon the end 16 by means of the left hand 21. This raises one side of the cap 14 so that it can be readily removed from the bottle.

I claim as my invention:

1. A bottle closure comprising: a thin paper cap secured in the neck of a bottle; and a string passing below the cap, and which is not attached in any way to said cap, but is frictionally held at two separated points between said cap and the neck of said bottle.

2. A bottle closure as in claim 1 in which both ends of said string project from the sides of said cap.

3. A bottle closure as in claim 1 in which one end of said string projects from a side of said cap.

In testimony whereof, I have hereunto set my hand at Los Angeles, California, this 4th day of March 1922.

CHARLES L. TURNER.
